UNITED STATES PATENT OFFICE.

SAMUEL ROSEN, OF UTICA, NEW YORK.

DESIGN FOR A COMBINATION LADLE AND STRAINER.

60,109.

Specification for Design.

Patented Dec. 27, 1921.

Application filed July 13, 1921. Serial No. 484,496. Term of patent 14 years.

To all whom it may concern:

Be it known that I, SAMUEL ROSEN, a citizen of the United States, residing at Utica, in the county of Oneida and State of New York, have invented a new, original, and ornamental Design for a Combination Ladle and Strainer, of which the following is a specification, reference being had therein to the accompanying drawing, forming part thereof.

The figure is a perspective view of the combination ladle and strainer, showing my new design.

I claim:

The ornamental design for a combination ladle and strainer, as shown.

In testimony whereof I have affixed my signature.

SAMUEL ROSEN.
